UNITED STATES PATENT OFFICE.

CLARENCE C. KEOWN, OF ORANGE FIELD, TEXAS, AND GEORGE SCHANZ, OF VINTON,
LOUISIANA.

OIL-WELL APPARATUS.

Application filed September 1, 1925. Serial No. 53,889.

This invention relates to oil well apparatus and has particular reference to the construction and arrangement of the screen, back pressure valve and wash pipe construction.

An important object of the invention is to provide a device of this character in which all liability of leakage through the bottom or back pressure valve is prevented and positive seal provided for the lower end of the screen after the back pressure valve has performed its function.

A further object of the invention is to provide a device of this character which may be inserted upon the end of the usual wash pipe and is connected to the wash pipe by an element so constructed that washing of the portions of the screen lying above the back pressure valve is possible after a plug has been inserted.

A further object of the invention is the provision of means to plug or seal the bottom end of a well screen with a rigid screw-threaded plug after the screen has been placed in position in the well.

These and other objects we attain by the construction shown in the accompanying drawings, wherein for the purpose of illustration is shown a preferred embodiment of our invention and wherein:

Figure 1 is a vertical sectional view showing a well casing in position and a plug likewise positioned, the parts being shown at the stage of the operation where the coupler 28 starts to disconnect from the plug;

Figure 2 is a combined side elevation of the coupler and plug.

Referring now more particularly to the drawing, in which we have illustrated the lower end of an oil well casing structure, the numeral 10 indicates the usual perforated screen, 11 a coupling engaged with the lower end of the screen and 12 a stand pipe or shoe by means of which the screen is supported at the proper height within the well. To the upper end of the screen, the usual casing 13 is connected. In connecting the screen and stand pipe or shoe 12, it is usual to insert therebetween a back pressure valve 14 opening toward the bottom of the well and in the present instance, I have illustrated a back pressure valve having a seat structure 15 exteriorly threaded, as at 16, for engagement in the coupling 11.

This seat structure embodies an upwardly

extending inlet 17, the upper end of which is flared, as at 18. The seat structure above described may be substantially that shown in the prior patent of Jarrett L. Cameron, No. 1,276,028, granted August 20, 1918, for well cleaning devices.

The interior of the extension 17 adjacent its upper end is provided with right-hand threads 19 for coaction with similar threads 20 formed on the exterior of a solid plug 21. This plug has interior left-hand threads 22, the purpose of which will presently appear.

The numeral 23 designates a coupling element adapted for engagement with the lower end of the usual wash pipe 24, this coupling having at its lower end an extension 25 which is threaded interiorly and exteriorly, as at 26 and 27, for a coupler 28 having at its lower end threads for coaction with the threads 22 of the plug 21 and the shield or sleeve 29 extending downwardly in spaced relation to the coupler 28. The coupler 28 has formed therein a plurality of openings 30 through which wash fluid may pass to the space between the coupler and the sleeve, this wash water finally passing out through the space 31 between the lower end of the sleeve and the upper end of the plug 21.

In the use of the device, after the shoe 12 has been seated and the screen is in the proper position, the wash pipe, with the plug 21 in position upon its lower end, is lowered until the threads 20 of the plug 21 are engaged with the threads 19 of the back pressure inlet 17. Before lowering the plug into the well, care is taken that the threaded connection at 22 is sufficiently tightly engaged so that it will permit engagement of the threads 19, 20, before the threaded connection at 22 will break. Under these circumstances, if the wash pipe is given continuous right-hand rotation, the result will be to first thread the plug into the inlet pipe 17 to seal the same and then break the connection at 22, unscrewing the coupler to permit withdrawal thereof. In event in lowering the device into the well, it is found, as is often the case, that the wash pipe and lower end of the screen are filled with sand, wash water is pumped through the wash pipe and because of the sleeve 31, will be directed downwardly so that it will wash out the upper end of the inlet pipe 17, permitting the plug to be placed in position.

After the plug is in position, the wash pipe may be withdrawn. It will be obvious that a device of this character may be relatively cheaply produced and is readily applied to or removed from position.

Since the structure thereof is capable of a certain range of change and modification without materially departing from the spirit of our invention, we do not limit ourselves to such specific structure except as herein-after claimed.

We claim:—

1. In combination with oil well apparatus including a screen, a back pressure valve at the lower end of the screen having a threaded inlet, a wash pipe and means for supporting upon the lower end of the wash pipe a plug having threads for engagement with the threads of the inlet of the back pressure valve, said plug connecting with the threads of the inlet and disconnecting from the wash pipe upon a predetermined operation of the wash pipe.
2. In combination with oil well apparatus including a screen, a back pressure valve at the lower end of the screen having an inlet facing into the screen, a wash pipe, a plug for sealing the inlet of the back pressure valve and means for supporting the plug from the wash pipe from which the plug is disconnected by continuation of the operation of seating the plug in the inlet.
3. In combination with oil well apparatus including a screen, a back pressure valve at the lower end of the screen having a threaded inlet, a wash pipe, means for supporting upon the lower end of the wash pipe a plug having threads for engagement with the threads of the inlet of the back pressure valve, said plug connecting with the threads of the inlet and disconnecting from said means upon a predetermined operation of

the wash pipe, said means for supporting the plug including a perforated coupler having threaded engagement with the plug at its lower end, a coupling with which the upper end of the coupler engages and a sleeve surrounding the coupler in spaced relation thereto.

4. In combination with oil well apparatus including a screen, a back pressure valve at the lower end of the screen having a threaded inlet, a wash pipe, means for supporting upon the lower end of the wash pipe a plug having threads for engagement with the threads of the inlet of the back pressure valve, said plug connecting with the threads of the inlet and disconnecting from said means upon a predetermined operation of the wash pipe, said means for supporting the plug including a perforated coupler having threaded engagement with the plug at its lower end, a coupling with which the upper end of the coupler engages and a sleeve surrounding the coupler in spaced relation thereto, the threads of said plug engaging with the threads of the inlet being opposed to the threads connecting the coupler with the plug.

5. In combination with oil well apparatus including a screen, a back pressure valve at the lower end of the screen having a threaded inlet, a wash pipe and means for supporting upon the lower end of the wash pipe a plug having threads for engagement with the threads of the inlet of the back pressure valve, said plug connecting with the threads of the inlet and disconnecting from said means by continuous rotation of the wash pipe in one direction.

In testimony whereof we hereunto affix our signatures.

CLARENCE C. KEOWN.
GEORGE SCHANZ.
